UNITED STATES PATENT OFFICE

FRANK P. DAUGHADAY, OF PROVIDENCE, RHODE ISLAND

CLASP FOR NECKTIES OR THE LIKE

Application filed September 29, 1931. Serial No. 565,723.

This invention relates to a clasp for securing together different pieces of material, such as holding a four-in-hand necktie or scarf to the shirt of the wearer and has for its object 5 to provide a construction in which different front jaw members may be assembled with a back jaw member by suitably forming one of the members so that it will have portions which may be folded about the other jaw member.

A further object of this invention is the provision of a clasp, the jaw members of which may be easily assembled by folding or bending the parts of one about the parts of 15 the other.

A still further object of this invention is the provision of a clasp construction having two parts which may be assembled one on the other by manipulation of the parts and without the necessity of a separate piece of material, whereby the cost of handling and production may be reduced.

With these and other objects in view, the invention consists of certain novel features 25 of construction, as will be more fully described, and particularly pointed out in the appended claims.

In the accompanying drawing:

Fig. 1 is a top plan view of the clasp.

Fig. 2 is a bottom plan view thereof.

Fig. 3 is a side elevation of the clasp.

Fig. 4 is a top plan view of the front jaw member in blank form.

Fig. 5 is a perspective view of the front jaw member bent into its operating position.

Fig. 6 is a top plan view of the rear jaw member.

Fig. 7 is a section on line 7—7 of Figure 2.

In the assembly of clasps such as for necktie holders as here illustrated, it is desirable 40 to provide an ornamental member for the front jaw to be observed when worn and to provide such a front jaw in forms which will represent or be typical of certain sports such, 45 for instance, as a golf stick as herein shown, a riding crop or whip, a racket or other emblematic instruments, and in order that these may be assembled with a back jaw member of unit form, I have provided a flattened end 50 portion on the front jaw, which has laterally

extending wings and which is doubled upon itself with the wing portions wrapped about the back jaw member so that no additional parts are necessary in handling for the assembly of the device; and the following is a 55 detailed description of the present embodiment of this invention, illustrating the preferred means by which these advantageous results may be accomplished.

With reference to the drawing, 10 designates generally the back jaw, and 11 the front jaw. The back jaw 10 is here shown as suitably formed from wire bent to provide side arms 12 and 13 with an inwardly extending portion 14, providing a loop 15 in which a 60 cam member 16 is pivoted for engagement with the fabric placed between the jaws and moved to vary the pressure on the fabric. The side arms of the rear jaw 10 are bent inwardly toward each other as at 17, with 65 parallel end portions 18 extending therefrom and adapted to lie in contiguous relation, one along the other.

The front jaw 11 consists of a shank portion 19 and is here shown in the shape of a 70 golf club having a head 20, although other desirable shapes may be provided. The shank is folded upon itself to form a resilient bend 21 with a portion 22 extending parallel with the front portion of the shank 19, while the 75 end of this doubled portion is flattened as at 23 and provided with integral wing portions 24 on either side thereof to embrace the ends 18 of the rear jaw and secure the two 80 jaw members together.

A rib 25 on the flattened portion 23 serves 85 to space the portions 18 and increase the gripping surface of the flattened portions and its wings on the portions 18 of the rear jaw member to more securely hold the same in assembled position.

By this construction a back member of any 90 desired configuration may be provided in desired multiples, while a variety of different front jaw members may be used, and each 95 provided with a portion to be wrapped about and assembled with the rear jaw member to provide a variety of tie clasps of different appearance and for selection to be used by 100 sportsmen interested in different types of

sport, or if desired, plain front jaw members of the desired ornamentation or shape may be provided.

5 The front jaw member disclosed is ornamental by certain embellishment 26 along the shank of the same, while ornamentation 27 may be provided on the face of the head 20 where desired to enhance the appearance of the construction.

10 The foregoing description is directed solely towards the construction illustrated, but I desire it to be understood that I reserve the privilege of resorting to all the mechanical changes to which the device is susceptible, 15 the invention being defined and limited only by the terms of the appended claims.

I claim :

1. A clasp for neckties or the like comprising front and rear jaws members, one of said 20 members being provided with a portion bent upon itself to furnish a portion in line with a portion of the opposite jaw member and to overlap a portion thereof, and wing portions extending laterally from one of said jaw 25 member portions along the overlapping part thereof to be folded about the other jaw member portion to clamp the jaw members together.

2. A clasp for neckties or the like comprising front and rear jaw members with portions in generally end to end relation, the front member being folded rearwardly to provide a resilient loop and overlap a portion of the rear member, wings extending laterally from 35 the rearwardly folded overlapping portion and embracing the end of the rear jaw member to secure the jaw members together.

3. A clasp for neckties or the like comprising front and rear jaw members, the front 40 jaw member being folded rearwardly to provide a resilient loop, the end of said rearwardly folded portion being flattened and provided with wings extending laterally therefrom and embracing the end of the rear 45 jaw member which extends over the flattened portion only and in overlapping relation to secure the jaw members together.

4. A clasp for neckties or the like comprising front and rear jaw members, the front 50 jaw member being folded rearwardly to provide a resilient loop, the end of said rearwardly folded portion being flattened and provided with wings extending laterally therefrom and embracing the end of the rear 55 jaw member to secure the jaw members together, said rear jaw member being provided with parallel wire portions and a rib on said flattened portion to extend partially between said wires.

60 In testimony whereof I affix my signature.
FRANK P. DAUGHADAY.
